(57) **CLAIM**

The ornamental design for an electric handtool, as shown.

DESCRIPTION

FIG. 1 shows a perspective view of the present design.
FIG. 2 shows a right side elevational view of the present design.

FIG. 3 shows a top plan view of the present design.
FIG. 4 shows a front elevational view of the present design.
FIG. 5 shows a bottom plan view of the present design.
FIG. 6 shows a left side elevational view of the present design; and,
FIG. 7 shows a rear elevational view of the present design.
